United States Patent Office

Des. 218,902
Patented Oct. 6, 1970

218,902

DOGHOUSE

James O. Kelley, Saline, Mich., assignor to Poly Fab, Inc., Madison Heights, Mich., a corporation of Michigan

Filed Aug. 4, 1969, Ser. No. 18,533

Term of patent 14 years

Int. Cl. D30—01

U.S. Cl. D30—1

FIG. 1 is a perspective front end view showing my new design.

FIG. 2 is a plan view thereof.

FIG. 3 is a side, elevational view thereof.

FIG. 4 is a front end elevational view thereof.

FIG. 5 is a rear end elevational view thereof.

FIG. 6 is an enlarged sectional view of a portion thereof, taken on line 6—6 of FIG. 4.

I claim:

The ornamental design for a doghouse, as shown.
